UNITED STATES PATENT OFFICE

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WITHDRAWING FEELER

Application filed January 15, 1929. Serial No. 332,640.

This invention relates to weft detectors more particularly usable on multicolor weft replenishing looms and it is the general object of the invention to provide improved 5 means for withdrawing the detector at the time of transfer.

In the usual form of multicolor weft replenishing loom the magazine and weft detector are located on the same end of the loom 10 and for this reason it is necessary to withdraw the feeler at the time of transfer to make a clear path for the outgoing and incoming bobbins. It has been customary in the past to accomplish this result by extending 15 a lug to the side of the detector and placed for engagement with an extension of the stud on which the transfer latch is mounted. With the type of feeler more particularly usable in connection with my present invention there is not only no opportunity 20 to conveniently add a lateral projection, but the detector itself projects high enough so that the use of the usual withdrawing means is rendered impossible.

It is a further object of my present invention to provide the transerrer arm with an auxiliary lug positioned to engage an up-standing portion of a weft detector carrier so that the latter may be moved forwardly at 30 the time of transfer to withdraw the feeler. It is a more specific object of my present invention to employ this auxiliary lug or finger as the means for applying the spring force which is depended upon to hold the transerrer normally in raised position, the connection between the spring and the finger being such as not to interfere with the withdrawing operation of the finger.

With these and other objects in view 40 which will appear as the description proceeds, my invention resides in the combination and arrangement of parts hereinafter described and set forth in the claims.

In the accompanying drawings, wherein 45 a convenient embodiment of my invention is set forth,

Fig. 1 is a vertical transverse section taken 50 through a magazine of the multicolor type having my invention applied thereto and

showing the parts in normal detecting position,

Fig. 2 is a vertical section on line 2—2 of Fig. 1,

Fig. 3 is a view similar to a portion of Fig. 1 but showing the parts in feeler withdrawing position.

Referring particularly to Figs. 1 and 2 I have shown a loomside 10 on which is mounted foot 11 on the weft replenishing mechanism 12. The latter may be provided with a plurality of compartments 13 down which reserve bobbins may move toward transfer position. The weft replenishing mechanism is provided with a hub 14 through which extends a relatively large stud 15 held in position by a set screw 16. The transerrer arm 17 has a hub 18 through which the stud 15 extends loosely and said hub has depending therefrom the usual pair of spaced arms 19 which support a stud 20 on which is pivotally mounted the usual latch holder 21. Mechanism not shown is employed at the time of transfer to lift the latch with respect to the arms 19 so that said latch will be in the path 75 of the lay L to effect a downward movement of the horizontal arm 22 of the transerrer.

A collar 23 is mounted on the right hand end of the stud 15 as viewed in Fig. 2 and supports a relatively large torsion spring 24 one end of which as indicated at 25 enters a portion of the collar. A cotter pin 26 holds the collar in fixed angular relation with respect to the stud so that the end 25 of the torsion spring is held in fixed position. The torsion spring has a horizontally extending end 27 which in the past has had engagement with one of the arms 19. The magazine parts heretofore described are of the usual construction and are of the type shown in prior Patent No. 1,030,748.

The weft detector may be of the type shown in my copending application Ser. No. 200,481 and comprises a bed 30 and a cap 31 between which is mounted for sliding movement a carrier 32. A weft detector 33 is mounted pivotally on the slide 32 by connections not shown.

In order to support the detector I may provide an arm 34 secured at its upper end by

set screw 35 to one of the tie rods 36 which is a normal part of the magazine construction. Said arm 34 has a horizontal foot 37 and a bolt 38 which extends through both the cap and bed of the detector and also the foot 37. By means of the structure supported by tie rod 36 the detector is held in position to be engaged by the advancing bobbin B carried by the shuttle S on each forward detecting beat of the loom.

From the matter thus far described it is understood that when the detector 33 engages a full supply of yarn the slide 32 will be moved forwardly substantially to the position shown in Fig. 1, but when the yarn is exhausted the detector will slide along the denuded bobbin and the slide 32 will remain at rest. It is obvious from an inspection of Fig. 1 that on transferring beats of the loom it is desirable to move the detector 33 forwardly and out of the path of both the outgoing and incoming bobbins, and it is an important object of my present invention to effect this result.

In carrying my invention into effect I provide the slide 32 with an upward extension 40 and form with the hub 18 a depending finger 41 which has a notch 42 to receive the horizontal end 27 of the torsion spring 24. The auxiliary finger 41 extends downwardly below the end 27 of the spring and lies over the cap and bed as shown more particularly in Fig. 2. It will be noted that the finger 41 is shorter than the arms 19, being necessarily smaller than the latter arms in order to be disposed above the cap and bed in position to engage the upturned end 40 of the slide 32.

At the time of transfer the transferrer arm will move downwardly from the position shown in Fig. 1 to that shown in Fig. 3, whereupon the finger 41 will be moved forwardly or to the left as viewed in Fig. 3 to engage the vertical extension 40 of the slide 32 to move the latter away from the lay. The effect of this operation is to move the detector 33 from the path of the outgoing and incoming bobbins.

From the foregoing it will be seen that I have provided a very simple means for withdrawing a weft detector of the type having a slide with an upwardly extending portion which is accessible only by a part moving over the bed and cap of the detector. It will further be seen that the depending finger 41 is the means by which the large spring 24 exerts its yielding force on the transferrer arm and that said finger is shorter than the usual arms 19, the withdrawing mechanism set forth herein being entirely independent of the latch and the parts by which the same is supported on the transferrer arm.

Having thus described my invention it will be seen that changes and modifications may be made therein by those skilled in the art without departing from the spirit and scope

of the invention and I do not wish to be limited to the details herein disclosed, but what I claim is:

1. In a withdrawing device for side slip feelers, a pivoted transferrer arm having a pair of spaced legs to support a latch by means of which the transferrer may be actuated, a forwardly movable slide, a detector arm pivoted to the slide to move in a horizontal angular direction at the time of indication of weft exhaustion, guiding structure for the slide, the forward end of the slide being bent upwardly, and a finger formed on the transferrer arm lying substantially over the slide and in alignment with the bent end of the latter so that when the transferrer arm is actuated said finger will engage the bent end to move the slide forwardly.

2. In withdrawing mechanism for a side slipping weft detector, a detector support, a slide movable forwardly in said support, a detector pivoted on the slide and having an angular movement in a horizontal direction at the time of indication of weft exhaustion, a transferrer arm pivoted above the detector support and movable in a vertical plane, means by which the transferrer may be moved in a vertical plane, the forward end of the slide being bent upwardly, and a withdrawing finger rigid with the transferrer arm lying over the slide and positioned to engage the upturned end of the slide when the transferrer has a transferring movement to move said slide and pivoted detector forwardly, said finger when engaging the slide moving in a vertical plane substantially at right angles to the plane in which the detector swings when giving indication of weft exhaustion.

In testimony whereof I have hereunto affixed my signature.

OSCAR V. PAYNE.
